PRESS BOX LOCKING MECHANISM

John Blewett, Dallas, Tex., assignor to The Murray Company, Dallas, Tex., a corporation of Texas

Application August 21, 1937, Serial No. 160,259

10 Claims. (Cl. 100—28)

This invention relates to new and useful improvements in press box locking mechanism.

One object of the invention is to provide improved means for locking a cotton press box in position during the tamping and baling operation.

An important object of the invention is to provide an improved locking mechanism of a simplified construction which is arranged so that it cannot be unlocked while the trumper is operating, whereby the press box can undergo movement only when the trumper is not operating; the mechanism also being such that the trumper cannot be operated unless the press box is in its locked position in proper alignment therewith.

15 A further object of the invention is to provide an improved mechanism of the character described wherein the locking of the box occurs automatically when the press box moves into its proper position, and means adapted to be actuated by the foot to release the locking means, whereby the unlocking of the box is facilitated and the operator's hands are free to perform other duties.

Still another object of the invention is to provide an improved locking mechanism for press boxes which is simple in construction and includes a minimum number of parts, the mechanism being positive in its operation and requiring no adjustments, as well as being readily applicable to any ordinary press box of the usual construction.

A construction designed to carry out the invention will be hereinafter described, together with other features of the invention.

35 The invention will be more readily understood from a reading of the following specification and by reference to the accompanying drawings, in which an example of the invention is shown, and wherein:

40 Figure 1 is a side elevation of a press box, having a locking mechanism constructed in accordance with the invention, attached thereto.

Figure 2 is a partial front elevation with a portion of the frame broken away to show the 45 latching means.

Figure 3 is an enlarged vertical, sectional view showing the locking plunger in its engaged position,

50 Figure 4 is a similar view with said plunger in its unlocked position.

Figure 5 is a horizontal, cross-sectional view, taken on the line 5—5 of Figure 3,

55 Figure 6 is an isometric view showing a portion of the linkage for operating the mechanism,

Figure 7 is an isometric view of the keeper block,

Figure 8 is a front elevation of the upper portion of the press box frame, illustrating the shifter and brake assembly,

Figure 9 is an enlarged front elevation of said assembly,

Figure 10 is a side elevation of said assembly, and

Figure 11 is a transverse, vertical, sectional view, taken on the line 11—11 of Figure 9.

In the drawings, the numeral 10 designates a vertical standard which has a platform or floor 11 bolted or otherwise secured thereto. The standard forms the main supporting structure of 15 a cotton press box assembly. A press box 12 is mounted to undergo rotation and is located above the platform 11. As is well known, the usual press box assembly includes two boxes which are secured together and are rotatable on a central 20 vertical post or shaft (not shown). The cotton trumper (not shown) is adapted to move downwardly within one box, while the usual press ram (not shown) moves within the other box, whereby cotton is tamped in one box while being compressed into a bale in the other box. As each bale 25 is completed, it is removed from the press box and the boxes are then rotated so that the tamped cotton is moved into alignment with the press ram while the box just emptied is moved 30 beneath the trumper. Cotton is then fed into the empty box and the trumper operated while the press is again operated at the same time to compress the cotton which has been tramped 35 upon the previous operation. The above method of baling cotton is common practice at the present time and forms no part of the present invention.

From the above, it will be seen that each time the boxes are rotated, they must be exactly aligned 40 with the trumper and with the press ram. Also, it is essential that they be firmly locked in this aligned position so as to prevent any accidental movement of the boxes while said trumper and ram are operating. The box 12 is mounted in the 45 usual frame 12' which is constructed of angle members which are bolted or otherwise secured together. The frame is, of course, rotatable with the boxes since said boxes are secured therein.

For holding the box 12 in its aligned position, 50 a keeper member or block A is secured to the lower end of the vertical end member of the box frame 12'. This member or block, as is clearly shown in Figure 7, includes an upwardly extending flange 13 through which bolts 14 extend. The 55

- bolts also pass through the end member of the frame 12' (Figure 3) and receive nuts 15 on their outer ends to securely fasten the block A to the frame 12'. A recess 16 which is substantially square in shape is formed in the outer face of said block. The recess extends from the top of the block A and terminates short of the bottom of said block. The sides of the block are bevelled inwardly toward the recess as shown at 17 in Figures 5 and 7, while a triangular shaped rib or lug 18 is preferably formed integral with the flange 13 and overlies the central portion of the recess 16. The top of said rib is bevelled as shown at 18'. By observing Figure 7, it will be seen that the rib 18 is of substantially the same width as the block A that is, its outer vertical surface lies in substantially the same plane as the outer vertical surface of the block, and the underside of the rib lies in the same plane as the top of the block. Since the keeper member or block A is fastened to the frame 12' of the box, said member or block will, of course, rotate with the box.
- The keeper member or block A is so positioned on the frame 12' that when said frame is moved to a position alining the box 12 with the trumper or ram, said member or block is moved into alinement with a locking plunger assembly B, which assembly is mounted on the vertical channel member 10 at the lower end thereof. The plunger assembly includes a housing or casing 20 which is formed with flanges 21 projecting outwardly therefrom. Bolts 22 pass through the flanges 21 and through the channel member 10 to securely fasten the casing to said channel.
- The lower end of the casing 20 is formed with a horizontally extending bore 23 and this bore extends from the inner end of the casing to a point near the outer end thereof. The bore is preferably square in cross-section and a plunger 24 is slidable therein. The channel 10 to which the casing is secured is formed with an opening 25 having substantially the same shape as the bore 23, and this opening is in alinement with said bore, whereby the plunger 24 may move outwardly through this opening to project beyond the inner surface of the channel 10. The plunger 24 is of substantially the same shape as the recess 16 in the block A and said block 50 is so positioned on the press box frame 12' that when the box is properly alined with the trumper (not shown), the recess 16 is alined with the plunger 24, whereby said plunger may engage said recess thereby locking the press box frame 12' of the channel 10 (Figure 3). When the plunger 24 is retracted, as shown in Figure 4, it will be evident that the frame 12' and the box 12 may be rotated since said plunger is disengaged from the block A.
- For controlling the movement of the plunger 24, a stem 26 extends through an opening 27 in the outer wall of the casing 20 and the inner end of this stem is threaded into the plunger, being located axially thereof. The inner end 65 of the plunger is recessed to form an annular shoulder 28 which surrounds the bolt 25 and a coiled spring 29 is confined between this shoulder and the end wall of the bore 23. The spring surrounds the stem 26 and constantly exerts its pressure to urge the plunger 24 outwardly of the bore and opening 25. Therefore, when the plunger 24 is moved inwardly of the bore it must move against the tension of the spring 29.
- From the above, it will be seen that the spring 75 29 acts to move the plunger outwardly of the
- bore 23 and for retracting said plunger a bell crank 30 is pivoted on a pin 31, which pin is supported in a bracket 32 preferably made integral with the casing 20. One arm 33 of the bell crank is formed with an opening 34 through which the outer end of the stem 26 extends. A washer 35 is confined on the extreme outer end of the stem 26 by nuts 36 and, as clearly shown in Figures 3 and 4, the washer abuts the arm 33 of the crank 30. By swinging the bell crank 10 so that the arm 33 moves outwardly with relation to the casing 20, it will be manifest that a movement will be imparted to the stem 26 which will move the plunger inwardly of the bore 23 under tension of the coiled spring 29. By swinging 15 the lever in the opposite direction, (Figure 3) so that the arm 33 engages the outer end of the casing 20, the coiled spring 29 is permitted to move the plunger 24 outwardly whereby its end projects through the opening 25 in the channel 20 10 and into the path of the keeper block A.
- For imparting movement to the bell crank 30, the other arm 37 of said crank has a vertically extending rod 38 pivotally connected thereto. The lower end of this rod has one end of a foot 25 lever 39 surrounding the same, this end of said lever being confined on the lower end of said rod between nuts 40. The foot lever is pivoted at its central portion on a pin 41 which is secured to the lower end of the channel member 30 10. Obviously when the outer end of the lever 39 is depressed, its inner end is raised which causes an upward movement of the rod 38 from the position shown in Figure 3. Upward movement of the rod 38 causes the crank arm 37 to 35 move upwardly swinging on the pivot pin 31. This moves the arm 33 of the crank 30 outwardly from the casing 20 and the engagement of the arm 33 with the washer 35 imparts a movement to the stem 26 and plunger 24, whereby the latter is retracted or moved inwardly of the opening 25 and bore 23.
- Assuming that the press box 12 and its frame 12' are locked in their proper position, the parts are in the position shown in Figure 3 with the 45 end of the plunger 24 engaging within the recess 16 of the block A. When it is desired to move the frame 12' so as to impart a rotation to the boxes, the operator merely depresses the foot pedal or lever 39 which causes a swinging 50 of the bell crank 30 to retract the end of the plunger 24 from within the recess 16. The end of the plunger moves to the position shown in Figure 4, whereby rotation of the frame 12' and box 12 is possible. The operator holds the pedal 55 or lever 39 depressed until such time as the keeper block A moves out of alinement therewith, whereupon the pedal or lever 39 is released which immediately permits the plunger 24 to again move outwardly of the bore 23 through the opening 25 in the channel 10. However, since the keeper member A has moved out of alinement with the plunger, no locking occurs upon the release of the lever 39.
- A second keeper block (not shown) is, of course, 65 provided on the opposite end of the frame 12' whereby when the frame completes one-half revolution, the second keeper member will move into alinement with the plunger 24. Since this other keeper member or block is exactly the 70 same, it is not believed that its illustration is necessary. As the rotation of the frame 12' is completed, the block A again moves into alinement with the plunger and as it does so the bevelled portion 17 of said block strikes the pro- 75

jecting end of the plunger, whereby said plunger is moved inwardly within the bore 23 under tension of the spring 29. At this time the bell crank 30 remains in its same position. The retraction or inward movement of the plunger 24 permits the block to move to the position shown in Figure 5 and as soon as the recess 16 in said block moves opposite said plunger, the coiled spring 29 again moves the plunger outwardly into engagement with said recess whereby the parts are again locked in position. They will remain in such position until the foot pedal or lever 39 is again depressed to retract said plunger. Therefore, it will be seen that the construction of the block A as well as that of the plunger 24 is such that an automatic latching occurs when the parts move into alignment with each other.

As before stated, the box 12 must be locked in a position in proper alignment with the trumper 20 (not shown) and also it is essential that the locking be complete before the trumper is operated. For this reason, it is desirable to provide means whereby the trumper cannot be operated until such time as the locking is complete and similarly, to provide means whereby the lock cannot be disengaged while the trumper is operated.

To accomplish this purpose, the control shaft 42 of the trumper mechanism is connected 30 through a suitable linkage with the latching or locking plunger 24, as will be explained.

The trumper control shaft 42 has one end connected to and controlling the engagement of a shifter and brake assembly whereby the trumper 35 is connected with a drive pulley or other source of driving power. The outer end of the shaft 42 has a pulley or grooved wheel 43 fastened thereon and a rope or cable 44 engages in the groove and is fastened therein. The ends of the cable which depend downwardly from the pulley 43, as shown in Figure 1, are provided with suitable handles 45. By exerting a downward pull on one or the other of the handles 45, it will be evident that the pulley 43 and shaft 42 40 may be rotated in either a clockwise or counter-clockwise direction. The shaft 42 is so connected with the shifter and brake assembly that its rotation controls the operation of the trumper, as will now be explained.

50 The shifter and brake assembly includes a driven pulley 42a which is keyed onto the trumper drive shaft 43a, said shaft operating the trumper in the usual manner. An idler pulley 44a is journaled on the shaft 43a, being freely rotatable thereon, and is of the same diameter as the pulley 42a. A drive belt 45a normally passes over the idler pulley and around the drive pulley P, which latter is driven from any suitable source of power. In this position, the pulley 44a is rotated, but no rotation is imparted to the trumper drive shaft 43a, since said pulley is freely rotatable thereon. At this time, a brake shoe 46a which is carried by an angular bracket 47a is engaging the driven pulley 42a to hold the same 55 against rotation. The bracket is pivotally mounted at 47b on a suitable support 47c. The brake shoe is held in braking position by a cam 48a which is contacting the outer end of the angular bracket 47a, as is clearly shown in Figure 9.

70 The cam is mounted on a rotatable stub shaft 49a.

A horizontal rod or shaft 50a extends outwardly from the press box frame adjacent the upper portion of the pulleys 42a and 44a and 75 has a belt shifter 51a slideable thereon. The

shifter has upwardly projecting arms between which the drive belt 45a extends and, manifestly, when the shifter is moved, the belt is shifted from the idler pulley 44a to the driven pulley 42a. When engaging the pulley 42a, it will be 5 obvious that rotation is imparted to the trumper shaft 43a. The shifter has connection through a rod 52a and arm 53a with the cam shaft 49a, whereby when the belt is moved onto the driven pulley 42a, the brake is released and when the 10 belt is moved onto the idler the brake is applied.

For moving the shifter 51a to control the operation of the trumper, the shaft 42 has a radially extending arm 54a which is connected by 15 a link 55a with said shifter. Thus, when the shaft 42 is rotated by means of the cable or rope 44, the shifter is moved to shift the belt from one to the other of the pulleys 42a and 44a. This 20 provides a clutching arrangement for operating and halting the trumper.

It is pointed out that the hereinabove described belt shifter and brake assembly is well known to those skilled in the art and that applicant makes no claim to this structure per se, 25 the same having been shown and described in order that the invention may be more readily understood. It is also noted that a belt shifter and brake assembly, having a very similar construction, is disclosed in United States Letters Patent No. 1,585,385, issued to Guy P. Hawkins on May 18, 1926.

The shaft 42 has an arm 46 (Figures 1 and 6) fastened thereon and the outer end of this arm 35 is connected to the vertical arm 47 of a bell crank 48 by means of a link 49. The link is pivoted to both the arms 46 and 47. The bell crank 48 is journaled on a transverse shaft 50 which is supported in an angle bar 10' which forms a part of the press box assembly frame. 40 The horizontal arm 51 has its outer end pivoted to the upper end of a locking rod 52. The rod extends downwardly through a sleeve 53 which is suitably secured by brackets 54 to the outer surface of the channel 10. The lower end of the 45 rod 52 projects from the lower end of the sleeve 53 and is adapted to enter a vertical passage or opening 55 which is formed in the top of the casing 20. As is clearly shown in Figures 3 and 4, the opening 55 extends from the top of the casing 50 downwardly to the bore 23, whereby said opening communicates with said bore.

The top of the plunger 24 is provided with a recess 56 which is adapted to register with the lower end of the vertical opening or passage 55 55 when said plunger is in its extended or locking position. Therefore, when said plunger is extended and the rod 52 moves downwardly through the passage 55, the extreme lower end of said rod may enter the recess 56, whereby movement 60 of the plunger is prevented by said rod. The linkage is so arranged that when the pulley 43 and shaft 42 are rotated to shift the belt 45a onto the pulley 42a to operate the trumper, the rod 52 is lowered into the recess 56 so that while 65 said trumper is operating, the plunger 24 cannot be retracted. When the wheel 43 and shaft 42 are rotated to shift the belt 45a onto the idler pulley 44a to halt the operation of the trumper, the rod 52 is raised, whereby its lower end is retracted from the recess 56 to permit the plunger 70 75 75 to be retracted by means of the crank 30 and foot pedal 39. Therefore, it will be seen that while the trumper is operating, the locking plunger 24 cannot be disengaged from the keeper block

A and the box 12 is securely locked in position in proper alignment with said trumper.

After the rod 52 has been raised, and the locking plunger 24 disengaged from the block A, and

- 5 while the boxes are being rotated, some means must be provided to prevent rotation of the wheel 43 so as to prevent operation of the trumper while the frame 12' and box 12 are moving from one position to another. To prevent this 10 rotation of the wheel 43, a spring pressed pin 57 is mounted within a horizontally extending bore 58 which is formed within the casing 20 above the bore 23. The bore 58 is provided with an enlarged portion 59 which is closed by a suitable 15 plug 60. The provision of the enlarged portion of the bore provides an internal shoulder 61 therein and the pin 57 is formed with a head 57' adapted to engage said shoulder. A coiled spring 63 is confined between the plug 60 and head 57' and constantly urges the pin 57 outwardly of the bore 58.

The channel member 10 is formed with an opening 64 which is in alignment with the outer end of the bore 58 so as to permit the outer end 25 of the pin 57 to extend therethrough. The pin 57 is normally in the extended position shown in Figure 4 and is spaced from the plunger 24 so that when said plunger is engaging in the recess 16 of the keeper member A, the rib or lug 18 of 30 the block A is engaging the outer end of the pin. Therefore, when the frame 12' is locked to the channel 10 by the plunger 24, the rib 18 is in engagement with the pin 57 and has moved the same into its retracted position under tension 35 of the spring 63, as clearly shown in Figure 3. At this time a transverse opening 65 which is provided in the pin 57 is aligned with the passage 55, whereby the plunger 52 which moves downwardly through the passage, may pass through 40 the opening 65 and engage the recess 56 within the plunger 24. However, when the keeper member A is disengaged from the plunger 24 and moves out of alignment therewith, the spring 63 immediately slides the pin 57 outwardly of its 45 bore, whereby the opening 65 in said pin is moved out of alignment with the passage 55. So long as the pin remains in this position, the rod 52 cannot be moved downwardly and since it is directly connected to the wheel 43 through the 50 linkage shown in Figure 6, it will be evident that said wheel cannot be rotated to operate the trumper. Therefore, the trumper cannot be operated until such time as the keeper member or block A again moves into alignment with the 55 plunger 24, at which time the rib 18 engages the outer end of the pin 57 to move the same inwardly so as to align the opening 65 with the vertical passage or opening 55. When this is done, the rod 52 may move downwardly through 60 the openings 55 and 65 and engage the recess 56 to lock the plunger 24 in position within the recess 16 of the member A.

With the above arrangement, it will be manifest that as the keeper member moves opposite 65 the plunger 24, it is automatically locked thereto since the plunger engages its recess 16. At the same time, the pin 57 is moved inwardly of its bore to the position shown in Figure 3. The frame 12' and the box 12 are thus locked in position in alignment with the trumper (not shown). The pulley 43 is then rotated by means of the cable 44 to start the operation of the trumper. At the same time, the rod 52 actuated by the wheel 43 moves downwardly to engage the recess 70 75 56 in the locking plunger 24. Therefore, so long

as the trumper is operating it is impossible to retract the plunger 24 and therefore the box 12 remains in its locked position until such time as the trumper is stopped through the reverse rotation of the wheel 43.

Such reverse rotation of the wheel retracts the rod 52 from the recess 56 and the opening 65. The foot lever or pedal 39 is actuated to retract the plunger 24 whereby the frame 12' may be rotated. As the keeper member or block A moves 10 out of alignment with the plunger 24, the rib 18 disengages the pin 57 to permit it to move to the position shown in Figure 4. Such movement of the pin 57 causes the opening therein to move out of alignment with the vertical passage 15 55 and the pin 57 remains in this position until such time as it is reengaged by the rib 18 of the keeper member or block A. While the pin is in this position, it will be evident that the rod 52 cannot move downwardly through the 20 passage 55 beyond the pin 57. Therefore, the wheel 43 cannot be rotated sufficiently to operate the trumper (not shown), while the boxes 12 are being rotated. Of course, as soon as the keeper member is again engaged by the locking plunger 25 24, its rib forces the pin 57 inwardly which again aligns the opening 65 with the passage 55 to permit downward movement of the rod 52 and a resultant operation of the trumper.

What I claim and desire to secure by Letters 30 Patent is:

1. A locking mechanism for a press box having a trumper movable therein including, a keeper mounted on the box, a stationary latching assembly having a plunger adapted to engage said keeper to lock the box in a fixed position in alignment with the trumper, and means free from connection with the plunger and operable by the trumper actuating means for engaging the plunger to prevent disengagement of said plunger 40 from the keeper while the trumper is operating.

2. A locking mechanism for a press box having a trumper movable therein including, a keeper mounted on the box, a stationary latching assembly having a plunger adapted to engage said 45 keeper to lock the box in a fixed position in alignment with the trumper, means free from connection with the plunger and operable by the trumper actuating means for engaging the plunger to prevent disengagement of said plunger 50 from the keeper while the trumper is operating, and means for preventing operation of the trumper actuating means when the locking plunger is not engaging the keeper.

3. A locking mechanism for a rotatable press 55 box having a trumper movable therein including, a keeper mounted on one side of the press box, a stationary latching assembly having a horizontally movable spring pressed locking plunger adapted to engage said keeper to lock the box 60 in a fixed position in alignment with the trumper, means for retracting said plunger from said keeper to permit rotation of the box, and a foot lever for actuating said retracting means.

4. A locking mechanism for a rotatable press box having a trumper movable therein including, a keeper mounted on the press box, a stationary latching assembly having a spring pressed locking plunger adapted to engage said keeper to lock 70 the box in a fixed position in alignment with the trumper, means for retracting said plunger from said keeper to permit rotation of the box, manually operable means for actuating the trumper, and means for preventing operation of 75

said manually operated means when the plunger is out of engagement with the keeper.

5. A locking mechanism for a rotatable press box having a trumper movable therein including, a keeper mounted on the press box, a stationary latching assembly having a spring pressed locking plunger adapted to engage said keeper to lock the box in a fixed position in alinement with the trumper, means for retracting said plunger from said keeper to permit rotation of the box, manually operable means for actuating the trumper, and means actuated by the last named means adapted to engage the plunger when the same is in engagement with the keeper to prevent retraction of said plunger while the trumper is operating.

6. A locking mechanism for a rotatable press box having a trumper movable therein including, a keeper mounted on the press box, a stationary latching assembly having a spring pressed locking plunger adapted to engage said keeper to lock the box in a fixed position in alinement with the trumper, means for retracting said plunger from said keeper to permit rotation of the box, manually operable means for actuating the trumper, means actuated by the last named means adapted to engage the plunger when the same is in engagement with the keeper to prevent retraction of said plunger while the trumper is operating, and means for preventing operation of the trumper actuating means when the locking plunger is disengaged from the keeper.

7. A locking mechanism for a rotatable press box having a trumper movable therein including, a keeper mounted on the press box, a stationary latching assembly having a spring pressed locking plunger adapted to engage said keeper to lock the box in a fixed position in alinement with the trumper, means for retracting said plunger from said keeper to permit rotation of the box, a foot lever for actuating said retracting means, manually operable means for controlling the actuation of the trumper, and a locking rod operated by said control means and arranged to lock the plunger against retraction when said plunger is engaging the keeper and while said trumper is operated.

8. A locking mechanism for a rotatable press box having a trumper movable therein including, a keeper mounted on the press box, a stationary latching assembly having a spring pressed locking plunger adapted to engage said keeper to lock the box in a fixed position in alinement with the trumper, means for retracting said plunger from said keeper to permit rotation of the box, a foot lever for actuating said retracting means, manually operable means for controlling the actuation of the trumper, a locking rod operated by

said control means and arranged to lock the plunger against retraction when said plunger is engaging the keeper and while said trumper is operated, and spring pressed means for preventing the rod from engaging the locking plunger when the plunger is not in engagement with the keeper while the press box is rotating, said means being actuated by the keeper when the same moves into alinement with the plunger.

9. A locking mechanism for a rotatable press box having a trumper movable therein including, a keeper mounted on the press box and having a recess therein, a stationary latching assembly having a spring pressed locking plunger adapted to engage within the recess of the keeper to lock the box in alinement with the trumper, means for retracting the plunger from the recess, a foot lever for actuating the retracting means, means for actuating the trumper to cause its movement within the box, a locking rod actuated by the trumper actuating means and adapted to engage the locking plunger when the same is within the recess of the keeper, whereby the plunger cannot be retracted while the trumper is operating, and spring pressed means adapted to be actuated by the keeper for preventing the movement of the rod into engagement with the plunger when said plunger is disengaged from the keeper.

10. A locking mechanism for a rotatable press box having a trumper movable therein including, a keeper mounted on the press box and having a recess therein, a stationary latching assembly having a spring pressed locking plunger adapted to engage within the recess of the keeper to lock the box in alinement with the trumper, means for retracting the plunger from the recess, a foot lever for actuating the retracting means, means for actuating the trumper to cause its movement within the box, a locking rod actuated by the trumper actuating means and adapted to engage the locking plunger when the same is within the recess of the keeper, whereby the plunger cannot be retracted while the trumper is operating, and a spring pressed pin above the plunger located in the path of the keeper and adapted to be depressed thereby when the plunger is engaged within the recess of the keeper, said pin having an opening therein which is alined with the locking rod when depressed, whereby the rod may pass therethrough to engage the plunger, said opening being moved out of alinement with said rod when the rod disengages the plunger and the keeper and plunger are disengaged, whereby re-engagement of the rod and plunger cannot occur until the keeper and plunger are re-engaged and said keeper again depresses the pin.

JOHN BLEWETT.
